UNITED STATES PATENT OFFICE.

EDWARD B. WASTIE, OF BILLINGS, MONTANA.

DISPLAY-PANEL.

1,184,800.

Specification of Letters Patent. Patented May 30, 1916.

Application filed March 6, 1915. Serial No. 12,659.

To all whom it may concern:

Be it known that I, EDWARD B. WASTIE, a citizen of the United States, residing at Billings, in the county of Yellowstone and State of Montana, have invented a new and useful Display-Panel, of which the following is a specification.

The device forming the subject matter of this application is adapted to be employed for displaying simultaneously, ceiling and side wall decorations, to the end that proper combinations may be made up either to suit the tastes of the designer or the tastes of the prospective purchaser.

So far as I am advised as to the state of the art, devices of the sort hereinafter disclosed have hitherto taken the form of a cabinet or rack of the general type shown in Patent No. 1,116,484 granted on the 10th day of November, 1914 to Sidney L. Ralph and one object of the present invention, therefore, is to provide a structure of the sort under consideration in which the wall-forming and ceiling-forming elements are displayed upon a single flat sheet of comparatively small size, the arrangement of the parts of the structure being such, however, that a third dimension will be simulated, thereby to throw into perspective, a portion of a ceiling, a portion of two angularly disposed side walls and a portion of the floor.

The invention aims to provide novel means whereby a portion of the structure will be made efficient at once as a means for giving a perspective effect and as an abutment whereby the ejection of the ceiling displaying slide or panel may be initiated.

The invention aims to provide a device of the type above mentioned in which panels may be interchangeably mounted upon a plate, thereby to render facile, the making up of different combinations disclosing ceiling-forming and wall-forming decorations in combination with those parts of a wall which are commonly assembled therewith.

It is within the scope of the invention to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the in-

vention herein disclosed can be made within the scope of what is claimed, without departing from the spirit of the invention.

In the accompanying drawings:—Figure 1 shows the invention in front elevation; Fig. 2 is a rear elevation; Fig. 3 is a fragmental longitudinal section; Fig. 4 is a fragmental rear elevation in the nature of a diagram; Fig. 5 is a front elevation showing a modified form of the invention; Fig. 6 is a rear elevation; Fig. 7 is a transverse section taken approximately on the line 7—7 of Fig. 5; Fig. 8 is a fragmental longitudinal section of the modification disclosed in Fig. 5.

Although the structure forming the subject matter of this application may be made in various sizes, it is preferably fashioned in small dimensions so that it may be readily handled. The device may embody a marginal frame 1 to the rear face of which is secured a display plate 2 which may be substantially co-extensive in dimensions with the frame 1. In the plate 2 is fashioned an upper opening 3 through which a ceiling display panel hereinafter mentioned is disclosed. The upper opening 3 ordinarily is bounded at its top and at its sides by the frame 1. In the plate 2 below the upper opening 3 is formed a lower opening 4 through which is adapted to be displayed a border panel hereinafter alluded to. The right hand end of the opening 4 ordinarily is defined by one side portion of the frame 1 as Fig. 1 will render evident. That portion of the plate 1 which remains intact between the openings 3 and 4 forms a rib 5 which may be decorated in any desired manner to simulate a molding or finishing strip lying between the ceiling and the border.

Disclosed through the upper opening 3 is a ceiling panel 6 which is slidably mounted on the rear face of the plate 2, removably, in an upper guide 7 and an intermediate guide 8, these elements being attached to the rear face of the plate 2. The invention comprises a wall panel 9 visible through the lower opening 4 and held in place removably and slidably by the intermediate guide 8 and a lower guide 10. Endwise movement of the panels 6 and 9 in one direction is limited by a stop 11 secured to the rear face of the plate 2.

The lower or border displaying opening 4 in the plate 2 does not extend entirely across the plate transversely, the plate being upwardly extended as shown at 12 past one

2
end 16 of the lower or border displaying opening 4. As clearly indicated at 14, the upwardly extended part 12 of the display plate 2 is prolonged within the contour of 5 the upper opening 3, the upper edge of the element 14 being downwardly and inwardly inclined, as shown at 15, with respect to the upper edge of the rib 5. Below the lower opening 4, the display plate 2 is decorated 10 in any suitable manner as shown at 17 to represent paneling, or any other decoration which constitutes a part of one side wall of the room. As shown at 18, that portion of the plate 2 which lies below and to 15 the left of the lower opening 4 is suitably decorated to indicate a side wall at right angles to the wall represented by the decorations at 17. The lower portion of the plate 2 is decorated or marked as shown at 19 to 20 indicate a portion of the floor.

That portion of the plate which is represented by the reference numeral 14 and the slanting edge 15 of such part exercise a double function. First, they serve to establish 25 proper perspective relations between the ceiling panel 6, the wall or border panel 9, the side wall 17 and the rectangularly disposed side wall 18. Second, the upstanding portion 14 of the plate which projects beyond 30 the upper edge of rib 5 forms an abutment coacting with the finger of an operator when the ceiling panel 6 is ejected, as shown in Fig. 4. When the ceiling panel 6 is started out of the guides 7 and 8, the pressure 35 of one finger of the operator is carried into the part 14 and the ceiling panel is not bent, distorted or torn.

The panels 6 and 9 are removable, and the invention contemplates the use of a plurality 40 of such panels, to the end that one panel of each sort may readily be replaced by another, thereby permitting proper combinations to be made up for inspection and comparison.

45 It is to be observed that the transverse axis of the lower opening 4 and the rib 5 do not lie at right angles to the longer dimension of the plate 2, but extend downwardly and to the left, as clearly disclosed in Fig. 1 and as outlined in Fig. 2, the perspective effect being further enhanced by this construction.

That form of the invention disclosed in Figs. 5, 6, 7 and 8 does not differ materially 55 from that form of the invention delineated in Fig. 1. In the figures under consideration, practically the only change brought about is that the border displaying panel 9 of Fig. 1 is replaced in Fig. 5 by a panel of sufficient size to disclose an extended wall area.

In Fig. 5 and in the remaining figures the frame appears at 21 and the display plate

is shown at 22. The upper opening appears at 23 and the lower opening at 24. The rib 65 which separates the ceiling from the side wall appears at 25 and the ceiling panel is shown at 26, the same being retained in an upper guide 27 and an intermediate guide 28. The wall panel 29 is held in the intermediate 70 guide 28 and in a lower guide 30 and the stop for the panels is shown at 31. A portion of the plate is upwardly extended as shown at 32 and protrudes as shown at 34 within the contour of the upper opening, the 75 inclined edge of the portion 34 appearing at 35. The inner edge of the lower opening is shown at 36 and the panel 29 which is disclosed through this opening is extended downwardly to a base board 37. A portion 80 of the plate to the left of the opening 24 is decorated as shown at 38 to indicate a rectangularly disposed side wall. The plate 22 is marked or decorated in its lower portion and upon its forward face to indicate a 85 floor, as shown at 39. Noting the point at which the reference character 40 is applied to Fig. 6 and observing the reference character 20 in Fig. 4, the function of the part 34 as a finger abutment for the panel 26 90 will be understood readily.

Those skilled in the art will understand that the fixed portions of the structure may be decorated in any desired manner, the removable panels being variously constructed. 95

Having thus described the invention, what is claimed is:—

In a device for displaying ceiling and side wall combinations, a plate provided with an upper, ceiling-disclosing opening, 100 and a lower, wall-disclosing opening forming a molding-defining rib therebetween; a ceiling panel; a wall panel; plate-carried guides for holding the panels for inspection through the respective openings; the 105 plate being upwardly extended along one end of the wall-disclosing opening and being extended within the contour of the ceiling-disclosing opening to form an abutment, the upper edge of which is extended downwardly and inwardly with respect to the upper edge of the rib, thereby to throw the ceiling panel into perspective and to throw into perspective so much of the plate as lies beyond said end of the wall-disclosing opening; and the abutment being adapted to coact with the finger of an operator to prevent a distortion of the ceiling panel when the ejection thereof is begun. 110

In testimony that I claim the foregoing 120 as my own, I have hereto affixed my signature in the presence of two witnesses.

EDWARD B. WASTIE.
